UNITED STATES PATENT OFFICE.

ALBERT T. PETTITT, OF WARNERVILLE, NEBRASKA.

DRAFT-EQUALIZER.

SPECIFICATION forming part of Letters Patent No. 460,487, dated September 29, 1891.

Application filed January 15, 1891. Serial No. 377,882. (No model.)

To all whom it may concern:

Be it known that I, ALBERT T. PETTITT, a citizen of the United States, residing at Warnevillle, in the county of Madison and State 5 of Nebraska, have invented a new and useful Draft-Equalizer, of which the following is a specification.

This invention relates to draft-equalizers for horse-powers; and it has for its object to 10 provide a device of this class which shall be simple in construction and by means of which the draft shall be equally distributed between the teams.

The invention consists in the improved 15 construction, arrangement, and combination of parts which will be hereinafter fully described, and particularly pointed out in the claims.

In the drawings hereto annexed, Figure 1 20 is a plan view of a draft-equalizer constructed in accordance with my invention. Fig. 2 is a sectional view taken on the line $x-x$ in Fig. 1. Fig. 3 is a perspective detail view of the connecting link or casting.

25 Like numerals of reference indicate like parts in all the figures.

Upon the main shaft of the horse-power, which is designated by 1, is mounted a lever or sweep 2, which extends on diametrically- 30 opposite sides of the shaft, as will be clearly seen in Fig. 1 of the drawings. To the outer ends of the sweep 2 are pivoted the levers or draft-bars 3, to the outer ends of which the whiffletrees 4 are attached in the usual 35 manner.

5 designates a casting consisting of a link, which is mounted upon the main shaft 1 above the sweep 2, upon which it is supported. The outer ends of the said link are provided 40 with brackets 6 to receive the inner ends of the draft-bars 3, which latter are connected pivotally with the ends of the link by means of pins or bolts 7 passing through the brackets 6 and through the ends of the link.

45 The pins or bolts 7 also serve for the attachment of the inner ends of the brace-rods 8, the outer ends of which are connected with the lead-bars 9. The inner ends of the latter are mounted upon the pins or bolts 10, by 50 means of which the levers or draft-bars 3 are connected pivotally with the ends of the sweep.

The operation of this invention will be readily understood from the foregoing de-

scription, taken in connection with the drawings hereto annexed. The link or casting 5, it will be observed, has a sliding movement upon the main shaft 1. In the event of one team pulling less than the other the draft will thus be equalized, and the tardy team 6 will at the same time be led up by the lead-bar 9, which is thrown in a forward direction, as will be seen by the dotted lines in Fig. 1 of the drawings. The construction of this device is simple, and it may be readily applied to horse-cars or baling-presses, and for other purposes to which horse-powers are customarily applied.

Having thus described my invention, what I claim is—

1. In a draft-equalizer for horse-powers, the combination of the sweep mounted upon the main shaft, the draft-bars pivoted to the opposite ends of the sweep, a link mounted slidingly upon the main shaft and having its 75 ends connected pivotally with the inner ends of the draft-bars, the lead-bars mounted pivotally upon the pivotal bolts of the draft-bars, and a brace-rod connecting the said lead-bars with the inner ends of the draft-bars and the 80 sliding link, substantially as and for the purpose set forth.

2. In a device of the class described, the combination of the sweep mounted upon the main shaft, the draft-bars mounted pivotally 85 upon opposite ends of the sweep, the lead-bars mounted upon the pivotal bolts of the draft-bars, the brace-rods connecting the lead-bars with the inner ends of the draft-bars, and a link connecting the inner ends of the 90 said draft-bars, substantially as set forth.

3. In a device of the class described, the combination of the sweep mounted upon the main shaft, the pivoted draft-bars, the lead-bars, the braces connecting the latter with the 95 draft-bars, and a link or casting mounted slidingly upon the main shaft above the sweep and provided at its ends with brackets connected pivotally with the inner ends of the draft-bars, substantially as and for the purpose set forth.

In testimony that I claim the foregoing as my own I have hereto affixed my signature in presence of two witnesses.

ALBERT T. PETTITT.
